CANDLE HOLDER

David B. Anderson, Jr., 5526 Douglas Drive,
Crystal, Minn. 55429

Filed Feb. 10, 1972, Ser. No. 225,360

Term of patent 14 years

Int. Cl. D26—01

U.S. Cl. D48—2

FIG. 1

FIG. 2

FIG. 3

FIG. 4

FIG. 5

FIG. 6

FIG. 1 is a view in perspective of a candle holder showing my new design;

FIGS. 2 and 3 are side elevational views thereof on a reduced scale, the sides opposite that shown being substantially mirror images;

FIG. 4 is a view in top plan thereof on a slightly reduced scale;

FIG. 5 is a view in bottom plan thereof on a slightly reduced scale; and

FIG. 6 is an axial section as seen from the line 6—6 of FIG. 3.

I claim:

The ornamental design for a candle holder, substantially as shown and described.
